Memphis
ATTORNEY

UNITED STATES PATENT OFFICE.

RICHARD GLASSER, OF SAN FRANCISCO, CALIFORNIA.

ENVELOPE OPENER.

Application filed May 4, 1922. Serial No. 558,481.

To all whom it may concern:

Be it known that I, RICHARD GLASSER, a citizen of the United States, and a resident of San Francisco, county of San Francisco, 5 and State of California, have invented a new and useful Envelope Opener, of which the following is a specification.

The present invention relates to means for opening envelopes and has particular reference to such means as are adapted to open the envelope by cutting off one of the edges of the same. The object of the present invention is to produce an envelope opener of the character described that will be positive 10 in action, simple in construction and insure uniformity in the width of the strip that is removed so that the danger of cutting off more than is necessary and of possibly injuring the letter contained in the envelope 15 is avoided. Further advantages will appear as the description proceeds.

The preferred form of my invention is illustrated in the accompanying drawing, in which Figure 1 shows a side elevation of 20 my envelope cutter, one of the covers being removed so as to disclose the interior; Figure 2 a top plan view of the same; Figure 3 a vertical cross section along line 3—3 of Figure 1; Figure 4 an enlarged detail section along line 4—4 of Figure 1, and Figure 30 5 an enlarged detail view of a portion of a blade used in my device. While I have shown only the preferred form of my invention, I wish to have it understood that 35 various changes or modifications may be made within the scope of the claims hereto attached without departing from the spirit of the invention.

A box-like structure (1) is secured to the 40 base (2) in any suitable manner, as for instance by the angle bar (3), surrounding three of the lower edges of the structure and secured to the base by means of screws (4). The box is rather tall, long and narrow, and 45 has the actual working mechanism including a cutting knife mounted therein, while a co-acting stationary blade (6) is secured in vertical position to a structure (7) also resting on the base (2) and extending into 50 the interior of the box (1), forming a platform (8) on which the envelope to be cut may be supported and slid inside the main structure until stopped by a longitudinal beam (9) secured to the rear wall (11) of 55 the box (1).

The cutting blade (13) secured to a longi-

tudinal plate (14) is supported over the cutting edge (6) in such a manner that when the blade is forced downward it will cooperate with the cutting edge in clipping off 60 a portion of the envelope interposed between the two cutting elements. The plate (14) is actuated in the following manner: A central shaft (16) is rigidly supported in the two blocks (17) and (18) secured to 65 the walls (11) and (19) of the box by means of screws (21) in vertically spaced relation to each other. A sleeve (22) slides on the shaft and is normally forced upward by a spring (23) surrounding the shaft. 70 The sleeve terminates in transverse pins (24) adapted to be engaged by the bifurcated lever (26), the end of which is pivotally supported on a transverse pin (27) extending between the two walls (11) and 75 (19). The free end of the lever which extends through the opposing side (28) of the box-like structure is provided with a handle (29), by means of which it may be manipulated. It will be seen that a pressure on the 80 handle (29) will cause the sleeve (22) to slide downwardly on the shaft (16) against the resistance of the spring (23), and that the sleeve, through the two links (31) pivotally connecting the same with the free ends 85 of two arms (32) pivotally secured to the stationary block (17), as shown at (33), will pull the free ends of said two arms downward, which latter motion will be transmitted to the longitudinal plate (14) through 90 the vertical links (34).

Mounted above the platform (8) so that its inner edge (36) is flush with the stationary cutting edge (6) is the holding member (37). The same is suspended from 95 two clips (38) projecting from the plate (14) by means of two bolts (39), a spring (41) having a tendency to press the holding member away from the clips.

The operation of the device should be 100 readily understood from the foregoing description. The envelope to be opened is placed on the platform (8) and pushed inside until its edge rests against the stop (9). The handle (29) is then pressed downward, actuating the sleeve (22) and forcing the same downward against the resistance of the spring (23). The sleeve, through the links (31) and the arms (33), 105 pulls the links (34) and with them the plate (14) downwardly. This motion is transmitted through the clips (38) to the 110

holding member (37), which is the first member to strike the platform (8) or the envelope lying on top of the same, whereby the latter is firmly held in its position. 5 The fact that the bolts (39) are adapted to slide in the clips (38) allows the plate (14) to continue its downward motion after the holding member (37) has come to a stop, and on the further downward motion the 10 blade (13) which is slantingly supported over the cutting edge will engage the envelope in co-operation with the cutting edge (6) and will clip off a marginal portion of the same with a scissor-like action; the 15 projection (40) at the lower end of the blade increases the length of this edge of the blade thus serving as a sliding bearing for the same to take the thrust due to the angular set of the knife. As soon as 20 the handle is released the spring (23) forces the sleeve (22) upward, which latter returns all the moving elements, including the arms (32) and the handle (29) to their original positions while the springs (41) on 25 the bolts (39) which were compressed during the cutting operation expand again and maintain the holding member (37) in spaced relation to the clips (38).

I claim:

1. In an envelope opener of the character 30 described, a drop blade, means for imparting vertical downward motion to said blade, comprising a rigidly supported vertical shaft, a spring supported sleeve slidable thereon, means for forcing the sleeve downward against the tension of the spring and an operative connection between the sleeve and the blade whereby the latter are forced down simultaneously.

2. In an envelope opener of the character 40 described, a drop blade, means for imparting vertical downward motion to said blade, comprising a rigidly supported vertical shaft, a spring supported sleeve slidable thereon, means for forcing the sleeve downward against the tension of the spring and an operative connection between the sleeve and the blade whereby the latter are forced down simultaneously, said connection comprising two horizontal arms extending from 45 central pivots, vertical links connecting the extremities of said arms with the blade and actuating links connecting the sleeve with the two arms.

RICHARD GLASSER.
